SOCK

Paul E. Johnson, Jr., P.O. Box 324, Marietta, Ga.
Filed Mar. 6, 1961, Ser. No. 64,162

Term of patent 14 years

(Cl. D47—7)

The FIGURE is a side elevational view of a sock showing my new design. The design on the sock is continuous, the side opposite to that shown being substantially the same.

I claim:

The ornamental design for a sock, as shown and described.
